UNITED STATES PATENT OFFICE

ALBERT O. SCHRAMM, OF ST. LOUIS, MISSOURI, ASSIGNOR, BY MESNE ASSIGNMENTS, TO THE AMERICAN LAUNDRY MACHINERY COMPANY, OF CINCINNATI, OHIO, A CORPORATION OF OHIO

LAUNDRY DRIER

Application filed November 21, 1928. Serial No. 320,812.

This invention relates to laundry driers.

An object of the invention is to provide an improved device for drying laundry comprising an enclosing cabinet for the laundry 5 to be dried, in combination with improved means for producing heated air and driving the heated air through the cabinet.

Another object of the invention is to provide a laundry drier of the character and 10 type mentioned wherein the cabinet is provided with a door or closure for the top, and means cooperating therewith to stop operation of the mechanism that forces the heated air through the cabinet automatically 15 and as an incident to the opening of the top of the cabinet.

Another object of the invention is to provide a top closure for a drying cabinet having means on opposite sides for engaging 20 and supporting the fabrics to be dried so that the fabric may be placed upon the upper side of the closure while the fabric on the opposite or inner side of the closure is being dried.

25 Other objects will appear from the following description, reference being made to the drawings in which.

Fig. 1 is a plan view of my improved laundry drier, part of the cabinet walls being 30 shown in section and the top closure being shown in open position.

Fig. 2 is a side elevation of the device.

Fig. 3 is a front end elevation.

Fig. 4 is a vertical cross sectional view 35 of the drying cabinet.

Fig. 5 is a vertical sectional view on the line 5—5 of Fig. 4.

Fig. 6 is a diagrammatic view of the electric circuit and the switch controlling the 40 same.

My improved drying cabinet comprises two side walls 1, a rear end wall 2, a front end wall 3 and a bottom wall 4.

The front end wall 3 has an opening there- 45 through which is surrounded by a frame 5 in which is mounted a device 6 constructed and arranged on the principle of an automobile radiator so that water or steam may pass freely therethrough. This radiator 6, being 50 constructed and arranged on the principle

of an automobile radiator, as stated, has a large number of openings through which air may be forced from the outside to the inside of the drying cabinet.

A manifold 7 has a number of tube or pipe 55 connections 8 opening into the upper side of the radiator 6 and controlled respectively by valves 9 whereby the amount of steam passing into and through the radiator 6 may be controlled and regulated. The manifold 60 7 receives steam from a steam supply pipe 10 leading from some suitable boiler or source of supply.

A number of pipes 11 open from the under side of the radiator 6 into an exhaust 65 manifold 12 from which the steam is conducted to waste or discharge through an exhaust pipe 13. A blower 14 is supported within the frame 5 adjacent to the outer side of the radiator 6. This blower is on a 70 rotary shaft 15 driven by an electric motor 16, the wiring 17 of which is controlled by a switch 18.

A confined space 19 (Fig. 5) is formed on the inside of the opposite end of the cabinet 75 by a box 20 having an inlet slot 21 near its upper edge. The space 19 opens into a number of pipes 22 which extend longitudinally through the cabinet and out through openings in the opposite end wall 3. Thus, the 80 hot air that is driven into the cabinet through the radiator 6 passes through the opening 21 into the enclosure 19 and thence to exhaust through the pipes 21. Accordingly, any fabrics that are supported in the cabi- 85 net are subjected to a continuous current of hot dry air so that the fabrics are quickly dried.

The closure for the upper end of the cabinet comprises a pair of spaced walls 23 forming opposite sides of a frame 24 which is rotatively supported near the top of the cabinet by axial extensions 25. On each side of the frame 24 fabric engaging devices 26 are secured and these may be made or composed of carding brushes. Thus, it is apparent that when either side of the closure is toward the inside of the cabinet a fabric may be secured to the outside of the closure while the fabric on the inside is being dried. 90 95 100

The wire 27 from the motor leads to a contact member 28, while the wire 19 from the switch 18 leads to connection with a spring element 29 (Fig. 6). A stem 30 is mounted in the wall 3 of the cabinet and projects through the spring member 29. The stem 30 has a collar 31 which is engaged by the spring element 29 so that said spring element is effective to move the stem 30 out of contact with the contact member 28 when there is no pressure against said stem 30. Near each side of the frame 24 I provide a bowed member 32 which will engage the end of the stem 30 and push said stem in opposition to the spring member 29 to contact with the contact member 28 and thus close the circuit through the motor when the switch 18 is closed. However, when the frame 28 is moved out of closed position it is obvious that the bowed member 32 will be moved away from the end of the stem 30 and will permit the spring member 29 to open the circuit by moving said stem 30 out of contact with the contact member 28. In this way operation of the motor 16 and the blower 14 is stopped automatically and as an incident to the opening of the cabinet. That is to say, whenever the frame member 24 is turned on its axis from closed position the motor and the blower are stopped. This is quite an advantage inasmuch as the air within the cabinet becomes very hot and if the blower continued to operate during the opening of the cabinet the operator would be subjected to the extreme discomfort of the intensely heated air.

In operation the frame 24 is turned to closed position and the fabric secured to the upper side thereof by engaging the fabric with the holders 26. Then, the position of the frame is reversed so as to place the fabric at the underside of the frame and within the cabinet. When the switch 18 is closed, the frame 24 now being in its closed position, the motor 16 begins to operate and thereby operates the blower 14 driving air through the hot radiator 6 to the inside of the cabinet and thence out through the exhaust pipes 22. When the fabric is dried the frame 24 is turned over to reverse position so that the dried fabric is at the outside and a fabric to be dried is on the inside of the cabinet. An incident to the movement of the frame 24 from closed position the motor is stopped, as above explained. As the frame 24 is moved to closed position to place the wet or damp fabric within the cabinet and the dry fabric in position for removal at the outside, the bowed element 32 closes the switch to the motor so that the motor automatically starts.

From the foregoing it will be seen that my invention is of a highly useful and simplified construction and possesses many advantages in that the motor is automatically

controlled for the most beneficial results. Obviously, the construction and arrangement of the parts may be varied without departure from the nature and principle of the invention.

I contemplate such variations as may be deemed useful and do not restrict myself unessentially in any particulars, but what I claim and desire to secure by Letters Patent is:—

1. A laundry drier comprising a cabinet having an opening thereto through one end wall thereof and having an open top, a frame surrounding said opening, a heater mounted in said frame, a device mounted in said frame adjacent to the outer side of said heater for forcing air through said heater and said opening into said cabinet, means for closing and supporting fabrics across the top of said cabinet, and means in said cabinet forming a passage for conducting air from said cabinet and having an inlet opening near the upper side of the cabinet and at the opposite end of the cabinet from said heater.

2. A laundry drier comprising a cabinet having an opening thereto through one end wall thereof and having an open top, a frame surrounding said opening, a heater mounted in said frame, a device mounted in said frame adjacent to the outer side of said heater for forcing air through said heater and said opening into said cabinet, means for closing and supporting fabrics across the top of said cabinet, a pipe extending from near the opposite end of the cabinet through said end wall for conducting air from said cabinet, and a device in said cabinet adjacent to the end opposite from said end wall for conducting air into said pipe and having an air inlet opening thereto near the top of the cabinet.

3. A laundry drier comprising a cabinet having an open top and having an opening thereto through one end wall for the admission of air to said cabinet, a device mounted in said frame for forcing air through said frame into said cabinet, means for closing and supporting fabrics across the top of said cabinet, a wall within said cabinet adjacent to the end opposite from said end wall forming a confined space having an opening thereto near the top of the cabinet, and a pipe opening and extending from the lower portion of said space longitudinally through the cabinet and through said end wall for conducting air from said space.

4. A laundry drier comprising a cabinet having an open top and having an opening thereto through one end wall for admitting air to said cabinet, means for supporting fabrics across the top of said cabinet, a device mounted in said frame for heating the air passing through said frame into said cabinet, a wall mounted in said cabinet and

- forming a confined space near the opposite end of the cabinet from said end wall and having an opening therethrough near the top of the cabinet for admitting air into said confined space, and a number of pipes opening from the lower portion of said confined space and extending longitudinally through the cabinet for conducting air from said confined space.
5. A laundry drier comprising a cabinet having an open top and having an opening into the cabinet through one end wall thereof for admitting air to the inside of the cabinet, a closure for the top of said cabinet, means for supporting fabrics in connection with the side of said closure that is toward the inside of the cabinet, a device in said opening for forcing air therethrough and into the cabinet, a wall forming a confined 10 space in the cabinet near the end opposite from said end wall and having an opening near the top of the cabinet for admitting air into said space from the inside of said cabinet, and a pipe opening from the lower 15 portion of said space and extending adjacent to the bottom of the cabinet for conducting air from said space and through the cabinet.
6. A laundry drier comprising a cabinet having an open top and having an opening 20 through one end wall thereof for admitting air into the cabinet, a closure for the top of the cabinet, means for supporting a fabric in connection with the side of the closure that is toward the inside of the cabinet, a frame surrounding said opening in said end wall, a heater mounted in said frame, a device mounted in said frame adjacent to the outer side of said heater for forcing air through said heater and said opening into 25 the cabinet, a wall in said cabinet forming a confined space near the end of the cabinet opposite from said end wall and having an opening for admitting air to said space from near the top of the cabinet, and a pipe opening 30 from the lower portion of said space and extending through the cabinet adjacent to the bottom thereof for conducting air from said space.
7. A laundry drier comprising a cabinet 35 having an open top and an opening through one end wall for admitting air into the cabinet, a device for supporting fabrics across the top of said cabinet, a wall located in the cabinet adjacent to and spaced from the end of the cabinet opposite from said opening and having an opening therethrough near the top of the cabinet for admission of air into the space beyond said wall, and means for conducting the air from 40 said space.
8. A laundry drier comprising a cabinet 45 having an open top and an opening through one end wall for admission of air into the cabinet, a device for supporting fabrics across the top of said cabinet, a wall lo-
- cated in the cabinet at a distance from the end wall of the cabinet opposite from said opening and having an opening through its upper portion to admit air into the space beyond said wall, and a pipe opening into said 50 space near the bottom of the cabinet for conducting air therefrom.
